(57) **CLAIM**

The ornamental design for a protective cover for LED module, as shown and described.

DESCRIPTION

FIG. 1 is a perspective view of a protective cover for LED module showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a sectional view taken along line 8-8 in FIG. 4; and,

FIG. 9 is a sectional view taken along line 8-8 in FIG. 4,

showing the design in use.

The broken lines shown in FIG. 9 to illustrate environmental

structures form no part of the claimed design.
